(57) **CLAIM**

The ornamental design for control buttons for video game controller, as shown and described.

DESCRIPTION

FIG. 1 is a top plan view of control buttons for video game controller showing our new design;

FIG. 2 is a top rear perspective view thereof;

FIG. 3 is an enlarged top front perspective view thereof;

FIG. 4 is a top front perspective view thereof;

FIG. 5 is a top right perspective view thereof;

FIG. 6 is a top left perspective view thereof; and,

FIG. 7 is a right elevational view thereof.

The bottoms of the buttons are flat and unornamented.

The broken line showing of a video game controller is included for the purpose of illustrating environmental structure and forms no part of the claimed design.

Our control buttons are characterized by five protruding buttons.

1 Claim, 7 Drawing Sheets
